(57) **CLAIM**

The ornamental design for a prosthetic component, as shown and described.

DESCRIPTION

FIG. 1 is a front upper perspective view of a prosthetic component.

FIG. 2 is a lower perspective view of the prosthetic component of FIG. 1.

FIG. 3 is a front view of the prosthetic component of FIG. 1.

FIG. 4 is a back view of the prosthetic component of FIG. 1.

FIG. 5 is a left side view of the prosthetic component of FIG. 1, of which the right side view is a mirror image thereof.

FIG. 6 is a top view of the prosthetic component of FIG. 1; and,

FIG. 7 is a bottom view of the prosthetic component of FIG. 1.

The broken lines shown are for environmental purposes only and form no part of the claimed design.
